FIBROID CASE

Herman L. Greve, Hollis, N. Y., assignor to International Mailing Tube and Wrapper Company, Long Island City, N. Y., a corporation of New York

Application December 1, 1937, Serial No. 177,516

5 Claims. (Cl. 229—16)

My invention relates to fibroid cases.

The object of my invention is to provide a cheap efficient fibroid case that can be shipped in a flat condition and folded into form by the user, and that can be closed by a flap portion which is flexible, and held in closed position thereby.

Further objects of my invention will be set forth in the specification hereinafter.

10 Referring to the drawings which form a part of the specification,

Fig. 1 is a view of a blank as it is formed prior to folding.

15 Fig. 2 is a perspective view of the case in its folded condition.

Fig. 3 is a perspective view of the carton or casing as it appears when ready to be used as a wall-case.

20 Fig. 4 is a plan sectional view of a corner of a casing, taken on line 4—4 of Fig. 3.

Fig. 5 is a view of a corner portion of a casing showing another construction of means for locking the flap portions of the case together.

25 Fig. 6 is a sectional view taken on line 6—6 of Fig. 5.

Fig. 7 is a view illustrating the use of both a clip and cement for holding the band forming the front upper side of the case together.

Fig. 8 is a sectional view taken on line 8—8

30 of Fig. 7 and showing the outer front band held by cement at the outer end of the band, the same construction being used at each end thereof to more firmly hold the corner portions together when the cover flap is forced under the band in interlocking the parts.

35 10 indicates the blank made of thin flexible material such as fiber-board which for most purposes is between one-sixteenth and one-eighth of an inch in thickness.

40 The blank is scored on the dotted lines to permit it to be easily folded.

Slots 11 and 12 are formed adjacent to each other and register when the flap 14 is folded over on the front side portion 13 as illustrated

45 in Fig. 3.

The metal clip construction shown in Figures 3 and 4, is made of stiff soft metal that can be bent after its free end is passed thru the slots 11 and 12, to the position shown in Figures 3 and 7, the clip being secured in fixed relation to the inner side flap 15 in the usual manner as illustrated at 16 in Figure 4.

Each of the front side flaps is cut on the bias as illustrated at 17, starting at a short distance from the corner of the case as illustrated at 18

to form rigid corner portions while permitting the front of the casing to be open down to the top of the banded portion 14 to permit easy removal of paper sheets deposited in the casing.

The band 14 presents a smooth upper edge 19 and serves to stiffen the entire front portion of the case.

When the cover portion of the casing is folded in the act of closing, the portion 20 overlies the band 14 and the end 21 is folded on line 22 and 10 the end 21 is flexed to permit it to be inserted under the band, thus holding the casing closed and held in fastened relation with the cover.

An aperture 23 is made in the end portion 21 to permit the case to be suspended from a nail 15 or hook fixed on a wall.

Referring now to Figures 5, 6, and 8, the means used to hold the band portion to the flaps 15 consists in forming a tab 24 integral with the band 14 and inserting it thru slots 26 formed in 20 the flaps 15 and 13 so that the free end of the tabs rest on the inner sides of the flaps 15, and by this construction I am able to construct a case without any further elements and thereby reduce the cost of manufacture materially.

25 In order to strengthen the construction of the band 14 I prefer to use cement 28 when using the integral tab construction, thus removing any strain from the tab in the act of bending the end portion 21 when inserting it under the band, 30 and the cement assists in making a more rigid lower edge 29 and so holds the end 21 in closer engagement with the portion 13.

Where the cement is used it may be applied and the parts joined thereby before shipment 35 while in its flat condition, or the cement commonly used may be moistened after shipment by the user at the time it is folded into a casing.

Where a large number of the blanks are to be shipped in a bundle, the elimination of the metal 40 clips and the cement surfaces not joined, the blanks rest in flat superimposed relation and require less room for a given number and also are of less weight than when metal clips are attached to the cases.

45 Having thus described my invention I claim as new:

1. A casing of the character described made of fibroid material formed from a single sheet folded to provide a pocket extending from the top to the bottom of the casing on rear side and open on its front side for a predetermined distance to permit easy access to the pocket, said casing formed with a band at its upper front edge comprising a folded portion which extends 50

across the casing to reinforce it and to provide a pocket on its inner side, means for securing the ends of said band together and to the front wall of the casing, and a cover portion having 5 a tab end which is scored and may be folded to extend upwardly under said band and rest in said pocket to hold the cover in its closed position.

2. The case construction defined in claim 1, 10 together with; the construction being such that the folding cover portion of the case overlies and conceals the means which hold the ends of the band together.

3. A casing of the character described made 15 of fibroid material formed from a single sheet folded to provide a pocket extending from the top to the bottom of the case on the rear side and is open on its front side from the top downward a predetermined distance, said casing 20 formed with a band at its upper front edge comprising a folded portion which extends across the front thereof and is provided with a laterally extending tab formed integral adjacent to its ends; said case having inner front flap portions provided with slots thru which the adjacent tabs may be passed and rest on the inner 25 sides of said flap portions.

4. The construction defined in claim 3, together

with; the cover portion having an end portion adapted to fold and extend upwardly under said band to hold said cover in closed position, and a portion extending over said tab portions of the band.

5. A casing of the character described made from a single piece of fibroid sheet material adapted for shipment in a flat blank condition and thereafter folded to provide a bottom portion and a back portion extending upwardly 10 therefrom to the top, a top portion hinged thereto and a front side flap portion extending downwardly therefrom and having its lower end folded to extend upwardly; end portions each of which carries a short flap which extends under the 15 front side of the casing; a front side portion extending from the bottom of the casing the upper end of which is folded back upon itself to form a band which extends across the casing at a distance from the top thereof and presents a smooth 20 top edge; and means carried by said short flaps and engaging said band to hold it to said flaps and to provide a pocket under said band to receive said upwardly extending end portion of the outer front flap and serves as a lock for the cas- 25 ing.

HERMAN L. GREVE.
